UNITED STATES PATENT OFFICE.

GEORGE L. WAITT, OF BUFFALO, NEW YORK.

CHAPLET FOR MOLDING.

Original application filed April 4, 1925, Serial No. 20,727. Divided and this application filed May 17, 1926. Serial No. 109,608.

The present invention is an improved chaplet for use in molding to prevent displacement of the core in molds or molding flasks.

6 The object of the invention is the production of a more durable chaplet giving more support and strength thereto, due to its particular construction, as a consequence rendering the chaplet compact, evenly balanced, 10 and utilizing all material of the blank from which it is made.

15 The invention further resides in the sundry details of construction, combination and arrangement of parts shown and described, and pointed out in the appended claims.

20 In this specification and the annexed drawings, the invention is disclosed in the form in which it is considered to be the best, but the invention is not limited to such form because it is capable of being embodied in other forms; and it is to be understood that in and by the claims following the description herein it is intended to cover the invention in whatever form it may embody within 25 the scope thereof.

25 In the drawings which show the preferred embodiment of the invention as at present devised:—

30 Figure 1 is a plan view of a blank from which the chaplet is made;

35 Figure 2 is a front elevation of the chaplet constructed from the blank shown in Figure 1;

40 Figure 3 is a horizontal sectional view taken substantially on lines 3—3 of Figure 2;

45 Figure 4 is a plan view of a blank for a slightly modified form of chaplet, having an opening in the rear upright or strut;

50 Figure 5 is a horizontal sectional view of the modified chaplet shown in Figure 4, and

55 Figure 6 is a perspective view of the chaplet.

Referring particularly to the drawings, in which like characters denote similar and like parts referred to in the specification, and referring particularly to Fig. 1, 8 indicates an elongated rectangular blank of desirable width and length to provide the chaplet shown in Fig. 2, which is substantially square.

The blank 8 is cut or otherwise formed to produce at its long side edges the outwardly oppositely projecting portions 9, which are located at a medial point of said edges 55 and ultimately form the wing flanges which

lie between the top and bottom plates 10 and 11.

The width of the portions or flanges 9 are such as is desired for the size of chaplet being made, and the blank is cut inwardly on the line *m*, *n*, *o* and *p*, from said end edges and on opposite sides of the wings 9, as clearly shown in Fig. 1. The portions 10 and 11, which form the top and bottom plates, are bent towards each other and on lines coincident with the cuts *m* and *o*, and *n* and *p*, to right angular position with respect to the center portion 12, which forms a relatively wide upright.

In order to permit a free flow of the molten metal about the chaplet, this upright 12^a may be perforated or provided with an elongated central opening 13, as shown in Figures 4 and 5.

The wing flanges 9 are bent on lines *q* and *r* to lie at right angles between the top and bottom plates 10 and 11, and to form struts extending transversely across the latter from the rear edge toward the front edge thereof for a distance at least, but preferably greater than one-half the width of said plates, as illustrated in Figures 3 and 5 where the free ends of struts terminate at a point adjacent the front edges of the plates 10 and 11. The outer or free ends 14 of the struts 9 are bent on lines *s* and *t*, respectively, to extend at any desired angle to the body of said struts 9, for the purpose of giving additional strength to the flanges or struts and to give support to the plates 10 and 11 in the direction of their length and at their front ends. As shown in Figures 2, 3, and 5, it is ordinarily preferred to extend the end portions 13 to be out of alignment with the upright 12 and 12^a so as to give support to the plates adjacent their side edges and to avoid obstructing the passage of molten metal between the struts or flanges 9.

From the foregoing it will be observed that chaplets of greater durability and strength are provided, using a minimum of stock and being compact in construction and well balanced. Manifestly with the present construction, a chaplet of any desired size can be made from a single strip of material with winged flanges or struts extending between the top and bottom from the rear to the front thereof, without increasing the width or area of the top and bottom plate, 110

which chaplet is of great advantage particularly in heavy work.

This is a divisional application of my co-pending application Serial No. 20,727, filed 5 April 4, 1925 (Patent No. 1,585,136 granted May 18, 1926).

Having thus described the invention what I claim as new and upon which it is desired to secure Letters Patent, is:

10. 1. A chaplet comprising top and bottom plates, a substantially straight upright connecting the plates at one edge of the latter and extending at right angles thereto, the outer side edges of said upright having laterally extending winged flanges thereon extending at an angle thereto and between said plates, said flanges being of a width to extend substantially across said plates.
20. 2. A chaplet comprising top and bottom plates, a straight upright connecting said plates at one edge thereof and spaced from the adjacent side edges of plates, struts formed by flanges on the opposite edges of said upright and extending at substantially right angles with respect to the uprights and lying between said plates, the free end portions of said flanges extending in an angle to the body of the struts.
30. 3. A chaplet comprising top and bottom plates, an upright connecting the plates at one edge of the latter, the outer side edges of said upright having laterally extending winged flanges thereon extending at an angle thereto and between said plates, said flanges being of a width to extend substantially across said plates, said upright being perforated.
35. 4. A chaplet formed from an elongated

blank of sheet material, the medial portion of the longitudinal edges of the blank each having thereon a lateral extension, the marginal end portions of the blank lying in superposed relation to provide top and bottom plates, the top and bottom edges of said extensions continuing into the blank by slits, 40 said extensions continued between said plates whereby the extensions form struts extending from the back edge of the chaplet to a point adjacent the front edge thereof.

5. A chaplet formed from an elongated 50 blank of sheet material, the medial portion of the longitudinal edges of the blank each having thereon a lateral extension, the marginal end portions of the blank lying in superposed relation to provide top and bottom plates, said extensions extending between 55 said plates whereby the extensions form struts extending from the back edge of the chaplet to a point adjacent the front edge thereof, the medial portion of the blank forming the upright having an opening therein.

6. A chaplet formed from an elongated blank of sheet material, the medial portion of the longitudinal edges of the blank each having thereon a lateral extension, the marginal end portions of the blank lying in superposed relation to provide top and bottom plates, said extensions extending between 65 said plates whereby the extensions form struts extending from the back edge of the chaplet to a point adjacent the front edge thereof.

In testimony whereof I have hereunto set my hand.

GEORGE L. WAITT.
